[57] CLAIM

The ornamental design for a hang tag, as shown and described.

DESCRIPTION

FIG. 1 is a perspective view of a hang tag showing my new design, with the strap broken away to indicate indeterminate length;

FIG. 2 is a front elevational view thereof;

FIG. 3 is a right side elevational view thereof, with the opposite side being a mirror image;

FIG. 4 is a top plan view thereof;

FIG. 5 is a bottom plan view thereof;

FIG. 6 is a rear elevational view thereof;

FIG. 7 is a perspective view thereof with the flap open to show substantially rectangular swatches of a material; and,

FIG. 8 is a front elevational view thereof with the flap open.
